BRICK SHAPES FOR BUILDING BLAST-FURNACE LININGS AND THE LIKE

Application filed July 12, 1928. Serial No. 292,305.

The invention relates to linings for blast furnaces and the like, and especially to bricks for building such structures.

Blast furnace linings and similar structures usually comprise circular courses of key bricks and straights laid in concentric rows. The walls may be of widely different thickness and diameter of opening, and there is no standard diameter. In order to build ideally laid linings an extremely large number of brick shapes and sizes would be required, and for reasons of economy, shapes have been standardized. The key bricks heretofore used have radial sides, but their design is arbitrary. The different sizes are not related to one another, or to the structures built therefrom. In consequence, much chipping and fitting is required to maintain the proper curvature when using these bricks. Thus they are not adapted for use in accurately building structures of every curvature; the bricks do not break joints in a proper manner in the rows of a course and between the courses; and it is impossible to space all of such bricks properly. So far as I am aware, no bricks have been devised thus far of which a few simple shapes and sizes suffice to properly construct linings of any desired thickness and diameter.

An object of the invention is to provide a plurality of standard brick shapes so related in shape and size that furnace linings of any size greater than a given minimum diameter may be built from a small number of shapes and sizes.

Another object is to provide a plurality of standard brick shapes so related to each other and to a given basic furnace opening as to minimize the number of different keys and straights required to construct a lining equal to or greater than that of the basic opening, and of any desirable thickness.

A further object is to provide a plurality of standard brick shapes so related to each other and to a minimum basic opening that variations in diameter of opening may be attained in substantially ideal manner, using a few different sizes and shapes, with little, if any, chipping or fitting.

Still another object is to provide a means

of relating the shape and size of keys and straights to each other and to circular structures to be built therefrom, in such a manner as to accomplish the foregoing objects, and which provides means for determining in advance the manner in which the brick shall be laid in any given structure to produce a substantially perfect lining.

It is among other objects of the invention to provide standardized related brick shapes of the type and by the means referred to which may be made to closely approximate the standard sizes now in use, which may be laid accurately and without the use of any other shape of brick than those provided by the invention, and which substantially eliminate the arbitrary spacing and the chipping heretofore necessary.

The invention may be described in connection with the accompanying drawings, which represent a preferred embodiment. Fig. 1 is a diagrammatic elevation of a blast furnace; Fig. 2 shows the manner of designing key bricks, in this case four in number; Figs. 3 and 4 are perspective views of two straights; Fig. 5 is a horizontal section through a cylindrical portion of the furnace, such as the hearth, taken on line V—V, Fig. 1; Fig. 6 is a vertical section taken on line VI—VI, Fig. 5, these two views showing the lining in place; Fig. 7 is an enlarged view of a horizontal sector of a lining, similar to VII—VII, Fig. 5, showing the number of brick of different sizes per row and a manner of disposing the same in all possible row positions, not staggered, of a course; Figs. 8 and 9 are respectively views similar to Fig. 7 showing two consecutive courses of brick and an end elevation of the same for an opening of minimum diameter; and Figs. 10 and 11 are views similar to Figs. 8 and 9, but for an increased diameter, such as on line X—X, Fig. 1.

The invention is predicated upon the use of a small number of basic keys and development bricks so related to each other and to a selected basic furnace opening as to serve for linings of any diameter equal to or greater than that chosen as basic. Their relation also is such that linings may be made of any

thickness which is a multiple of a chosen brick length factor.

The basic keys comprise two bricks which are sectors of an annulus of the chosen basic minimum diameter. They have the same 5 central angle and inner width, and their lengths, which are different, represent integral multiples of a given length factor. The outer width of these basic keys is, of course, 10 dependent upon their length, because of their sector basis. The inner width of these keys is chosen such that when an integral number are laid side by side they will exactly turn a circle 15 of the basic diameter. The basic diameter is the minimum furnace opening which can be 20 built from these brick, and is preferably chosen as the smallest which is commonly used.

The development brick are used in conjunction with the basic keys for building the 25 outer rows of a course, and also in connection with basic keys for expanding the basic opening. The development brick are definitely related to the basic keys. This relation is such that given combinations will exactly 30 occupy a selected extent, such as an integral sector of the lining, and also such that the two types may be used in selected combinations to provide any desired increment in diameter greater than, or decrement down to, 35 the basic diameter. Preferably the development brick comprise two growth keys and two straights, although basic keys may in some cases be used without growth keys. Likewise, four straights may be used instead of two. 40 The inter-relation between all of these bricks and their manner of use follow certain definite relations fully set forth hereinafter.

Having reference now to the drawings, Fig. 1 is a conventional representation of a blast 45 furnace comprising a refractory lining 2 forming stack and hearth portions 1 and 1^a surrounded by a metallic outer shell 3, and a bosh portion 1^b. The lining, which embodies the invention, comprises horizontal circular 50 courses each comprising a plurality of concentric rows of bricks designed and laid in a definite manner.

The lining comprises basic keys and development brick. According to the preferred 55 embodiment the development brick include both growth keys and straights, two of each type being used. The straights may comprise two used for filling, and two for expanding. Filling straights are used for filling and completing 60 the outer rows of a course, and expanding straights are used to expand the basic diameter. However, in order to reduce the number of brick styles, it is preferred to make a single type of straights which will satisfactorily accomplish both purposes. The relations existing between the various brick are as follows, reference being had to Figs. 2, 3, 4 and 7.

The basic keys 1 and 1^a are laid out as 65 sectors of an annulus of inner diameter D, where

D is a selected basic or minimum furnace or lining opening. The same central angle a is included by each of the keys, and each has the same inner width w . This inner width is chosen such that an integral, desirable number n of the basic keys will exactly fill a ring of diameter D. This follows readily from the equation:

$$w = \frac{\pi D}{n}$$

The number n is chosen to give w a suitable value, preferably approximately that now used.

The length of the keys is based upon a length factor L, which may be and preferably is, a commensurate divisor of the brick lengths now used. Keys 1 and 1^a are, for purposes of securing proper breaking of joints, of different length. These lengths are integral multiples of the factor L and in the example shown the length of key 1 is 2L, and that of 1^a is 3L, although other values may be chosen. The width of the outer ends of the basic keys depends upon their length. For example, if i is the n th part of the circumference of a circle whose radius is L,

$$i = \frac{2\pi L}{n}$$

and if the radius is increased by L, the circumference increases by an amount equal to i . Thus the outer widths are $w+2i$ for key 1, and $w+3i$ for key 1^a. From this it will be understood that the basic keys will exactly fill the inner rows of basic minimum diameter D, and that this is the smallest opening which can be built from those keys.

The growth keys 2 and 2^a are likewise sectors of an annulus, concentric with but of greater radius than that of the basic ring by an amount equal to $b'L$ where b' is equal to or an integral multiple of a factor b described hereinafter. These keys are laid out with the same central angle and of the same 105 lengths as the basic keys, and their inner widths will be alike and equal to $w+b'i$ as appear from the foregoing considerations. The outer lengths, likewise, will be $w+(b'+2)i$ for the keys 2, and $w+(b'+3)i$ for the keys 2^a.

The straights are shown in Figs. 3 and 4, as rectangular bricks 3 and 3^a whose lengths are respectively 2L and 3L. For maintaining uniformity of construction these brick 120 are also of equal width, represented as ki , where k is an integral multiple of the factor b described hereinafter. The thicknesses of the keys and straights may be those now used.

For purposes of illustration, let D=14 feet; and L=4½ inches, a common divisor of the two standard lengths heretofore used, so that the lengths 2L and 3L are those now used, or 9 and 13.5 inches. In order to provide 130

basic keys having an inner width approximating present practice, a convenient integral number of which will fill the basic ring, n is in this case chosen as 114. From the 5 equation

$$w = \frac{2\pi D}{n}$$

it follows that w , the inner width of keys 10 and 1^a , is 4.63 inches. It also follows that $i=0.248$ inches; and if $b'=6$, the inner width 15 of the growth keys 2 and 2^a , $(w+b'i)$, is 6.118 inches. A suitable width for the straights is given by assuming $k=24$, in which case $ki=5.9525$ inches, or approximately 6 inches, the width now used. Other dimensions may 20 of course be used where desirable or necessary, the various sizes being readily determinable.

25 The benefits of the invention are secured in part by the manner of assembling these brick to form a structure of given size of opening or wall thickness, or to vary those dimensions, or the uniformity of the opening, and in all cases to provide for breaking of all joints. This manner of disposing the 30 bricks is understood most readily by considering a sector or block of a course, which represents an integral part of the course. To 35 this end, a sector VII—VII, Figs. 5 and 7, is chosen, which contains a convenient number of basic keys in its inner row. This number is represented by the previously mentioned factor b , which must be an integral portion of n . Each row in a given sector of 40 a course will, in accordance with the invention, contain b basic keys, growth keys, or basic and growth keys combined.

The block shown in Fig. 7 is taken as being 45 of basic minimum diameter, that is, its inner diameter is that of the ring which forms the basis for the basic keys. The factor b is in this case equal to 6, this value being suitable for lay-out purposes, and also in this base 50 $b=b'$. Six basic keys 1 will exactly fill the inner row of this block; and there will be 55 n , or 19 such blocks in the illustrative example, 60 each being an exact duplicate of the others.

55 The successive rows in the block will be made up by replacing basic by growth keys, each of the latter increasing the inner width of the row by an amount equal to $(w+b'i)-w$, or $b'i$, which is in this case $6i$, or 1.488 inches. 60 When, through this operation, a row contains only growth keys, further expansion is attained by the combined use of basic and growth keys and straights. It will be understood that where basic keys 1 or growth keys 65 2 are referred to, keys 1^a and 2^a respectively, may be used, their inner widths being the same as that of the corresponding key.

65 The walls may be built up to any desired thickness which is a multiple of the length factor L , by suitable choice of the bricks, and

because of their relation to each other, these bricks will accurately fill every row up to any desired wall thickness.

The inner width of each row of a sector or block is, according to the invention, equal, or substantially equal, to the outer width of the next row inwardly. That this object is actually and readily achieved is shown by Fig. 7, in which the bricks are numbered as described above. The inner row consists of 70 six basic keys 1, so that its outer width is $6(w+2i)$, or $6w+12i$. The next row consists of four basic keys 1, and two growth keys 2, and its inner width equals $4w+2(w+6i)$, which reduces to $6w+12i$, the outer width of the inner row. It can be shown readily that 75 each row outwardly follows the same progress as developed for rows 1 and 2.

The number of the various brick required for each row of the blocks, either of the examples given, or in any other case, can be calculated readily. Let x = the number of basic keys, y the number of growth keys, and z the number of straights in a row, and let p be the row position, or number of unit lengths 80 L from the inner end of the row considered to the inner end of the inner row, which latter is assumed to be a zero position. Then $x+y=b$, or the keys per row, which is constant for every row in the sector. The number of bricks for any row will be found by 85 means of the equation

$$b(w+ip) = xw + y(w+b'i) + zhi$$

which reduces to

$$pbi = zki + yb'i + (x+y-b)w$$

and since $x+y-b=0$, this becomes

$$pbi = zki + yb'i,$$

and since according to definition b and b' are always integral factors of k , and the total number of keys in any row of a sector is constant, it is always possible to readily find integral values of y and z which will satisfy this 105 equation.

The layout of Fig. 7 is used to show how the 110 bricks may be disposed in successive rows of a course to give any desired thickness with each row fitting the adjacent rows properly. 115 As shown there, the end joints do not break in an ideal manner. This feature of the invention is secured in the manner shown in Figs. 8 and 9, in which the end joints break in a fully proper manner, both vertically 120 and horizontally. These views represent a block similar to that discussed hereinabove, the opening again being of basic diameter. Two courses 10 and 11 are shown, the lower 125 being represented by dotted lines in Fig. 8. The lower course 10 of the block is started by laying six basic keys 1. The outer width, as before, is $6w+12i$. The next row of this course is displaced laterally about one-third of a brick width, as seen in Fig. 8. This row 130

consists of the longer keys 1^a and 2^a, and to secure perfect fit this row will consist of four basic keys 1^a and two growth keys 2^a, their total inner width being $6w + 12i$. Successive 5 rows in this course will then be laid in the manner explained previously, as shown in the drawing. The brick in any row are of the same length, and straights are added when necessary. The basic and growth keys, and 10 straights, in rows subsequent to the inner row are disposed as symmetrically as possible to assist in breaking joints.

The next course, 11, commences with an inner row of six basic keys 1^a, their outer width 15 being $6w + 18i$. This is followed by a row of three keys 1^a and three growth keys 2^a, whose inner width totals $6w + 18i$, the same procedure being followed up to the last row, when the course is completed by a row of 20 bricks 1, 2, and 3, as shown. The inner row 25 of this course is displaced about one-third of a brick width with respect to the inner row of the course below it, and successive rows are disposed in the manner described for course 10.

From this is will be seen that the preferred practice is to lay successive courses in which the limiting rows of a course are of different length from those in the same position in adjacent courses. Also, all the 30 bricks in any one row are of the same length, and adjacent rows are laterally offset. In laying successive courses, the inner rows are staggered about one-third of a brick width, and by virtue of this, the spacing in consecutive rows of a course, and overlapping of vertical rows, all joints break in a proper and theoretically perfect manner. In building up a cylindrical lining 35 following Fig. 8, the course laid on course 40 11 will be similar to course 10, and so on, to the height desired. Other layouts intermediate the limiting rows may be used with 45 equally satisfactory results.

The examples discussed thus far have related to linings having a cylindrical opening of the basic minimum diameter. The preferred manner of expanding this diameter to obtain larger openings is to insert 50 one or more straights in the inner row of one or more blocks, the number of keys remaining the same, and a similar number of straights are inserted in all subsequent rows of the block or blocks. These are, of course, 55 extra straights over and above those which would normally be used in outer rows. Each straight, by virtue of the relations previously explained, inserted in the inner row will increase the diameter of the opening 60 by an amount equal to $\frac{ki}{\pi}$. In the illustrative case chosen this is equal to 1.894 inches. By so adding straights the diameter can, by regular increments, be made as 65 large as desired. Where a plurality of

straights are used for this purpose, they are spaced at approximately regular intervals about the circle.

This could be accomplished by using an expanding straight, of different width than 70 the filling straight, to give a larger or smaller increment than the straights 3 and 3^a. However, as pointed out previously, satisfactory results are obtained, and with 75 fewer sizes of brick, by using the straights illustrated for both purposes.

This manner of expanding is illustrated in Figs. 10 and 11 in which each row of the courses 10^a and 11^a contains a straight 15 or 15^a for expanding, the layout being 80 otherwise as shown in Fig. 8. Although these straights are, as stated, preferably straights 3 and 3^a, a different numeral is used to represent them, to indicate that they are used in addition to the brick disposition 85 of Fig. 8.

The method just described may be used to attain larger diameters for cylindrical openings, or to expand gradually in making sloping or conical openings. The reverse of 90 the foregoing procedure, that is the removal of straights, is used for decreasing the diameter of an expanded opening. Another means of laying the brick to form 95 sloping inner walls, where the use of straights might produce too abrupt changes, is as follows: A basic key 1 (or 1^a) in the inner row is replaced by a growth key 2 (or 2^a), and the successive rows calculated in the manner previously explained, adding 100 $b'i$ to the left side of the equation. The value of $b'i$ is, of course the circumferential increment produced by the substitution referred to. That is, it is $w_2 - w$, where w and w_2 are respectively the widths of the basic 105 and growth keys. Or, $(w + b'i) - w = b'i$. In the example given, $b'i$ equals $6i$, and the straights are $24i$ wide. Thus the use of a growth key instead of a basic key will produce but one-fourth the increase in diameter 110 that is produced by adding a straight.

It will be understood that other brick dispositions may be used than those illustrated and described, and that other concrete 115 values may be used than those given for purposes of illustration, without departing from the scope of the invention. Likewise it will be understood that the invention is not limited to the use of four keys and two 120 straights. Six keys can be used, for example, and the use of four straights as in present practice has been discussed. Also, the invention comprises the case where $b' = 0$, that is, when the growth keys and 125 basic keys are similar. However, I prefer at present to use the four keys and two straights described in detail, as these may be used in simple and accurate fashion, and still the number of sizes is minimized.

The invention provides brick for use in 130

erecting blast furnace linings and similar structures, of which a minimum number of sizes and types may be used for building a structure of any size greater than a basic minimum diameter, which latter may be of any desirable size. They may be used for building cylindrical or sloping walls with equally satisfactory results. The structures obtained are more satisfactory than those heretofore erected, because more perfect bonding and fitting is possible. Also the invention gives greater economies in erection costs and other expenses. By providing a minimum number of standard sizes which will accurately fit any desired condition, smaller stocks of sizes are necessary, estimating can be done with great accuracy, and definite layouts can be made, which can be followed with little, if any, chipping or fitting. This increases the speed of erection.

I claim:

1. A circular tapering furnace lining built up from basic key bricks comprising sectors of a ring and growth key bricks, said bricks being laid in horizontal courses each comprising a plurality of concentric rows, said basic keys including two sizes of different length and of the same inner width, an integral number of which will turn a circle of minimum basic diameter, said growth key brick comprising two sizes of equal inner width and of different lengths equal to those of the basic key bricks, all four of said brick sizes having their longer sides radial to a common center, each row of a course containing an equal number of keys, the inner diameter of one row being the same as the outer diameter of the next row inwardly, the rows outwardly in a course being increased in diameter by the use of growth key brick, the brick in successive rows of a course breaking joint, each row of a course being offset laterally with respect to consecutive rows and to those in adjacent courses so as to break joints vertically, and the rows of successive courses overlapping, whereby vertical joints at the ends of the brick are broken.

2. A tapered brick furnace lining circular in horizontal section comprising horizontal courses each consisting of a plurality of concentric rows of bricks, said brick comprising straights and keys, the straights including two lengths of equal width, the keys comprising a basic set and a growth set, said basic set comprising sectors of a basic ring in two lengths of equal inner width, an integral number of which when laid side by side will turn a basic circle equal to a minimum furnace opening, said growth set comprising sectors of a ring concentric with and of greater diameter than said basic ring and also in two lengths of equal inner width, the lengths of said keys being the same as that of the straights, each row in a course containing

the same number of keys, the inner diameter of a row of a course being equal to the outer diameter of the next row inwardly, the diameter of the rows up to that of the growth ring being increased by replacing basic keys by growth keys, and beyond that diameter by also inserting straights, said straights each increasing the diameter by an amount equal to the width divided by π , the bricks in adjacent rows of a course breaking joint, the bricks in successive courses being overlapped and laterally offset, whereby to break all end and side joints vertically.

3. A furnace lining of non-uniform diameter comprising brick laid in horizontal courses each comprising a plurality of concentric circular rows, said lining comprising keys and straights, said keys comprising a basic set in two lengths of equal inner width representing sectors of a ring, an integral number of which will turn a circle equal to a basic minimum furnace diameter, and a growth set in two lengths of equal inner width also sectors of a ring which is concentric with and of greater diameter than said basic ring, said lengths being the same in each set, each row of a course containing the same number of keys, and the rows in a course outwardly from its inner row being developed by substituting growth keys for basic keys and adding straights, according to the equation

$$pbi = zki + yb'i$$

where b is the number of keys per row in a given integral sector of a course, p is the row position, i is the increase in width of a key per unit length factor, y and z are respectively the number of growth keys and straights, ki is the width of a straight, and $b'i$ is the difference in width of the basic and growth keys.

4. A tapering brick furnace lining circular in horizontal section comprising horizontal courses each consisting of a plurality of concentric rows of brick, said brick comprising straights and keys, the straights including two related lengths of equal width, the keys comprising a basic set and a growth set, said basic set being sectors in two lengths of equal inner width of a basic ring the diameter of which is that of a basic minimum furnace opening, said growth set comprising sectors in two lengths of equal inner width of a growth ring concentric with and of greater diameter than said basic ring, the lengths of said keys being the same as the length of the straights the basic and growth keys being equiangular, the inner row of a course of basic diameter containing only basic keys, and the successive rows of said course having growth keys substituted for basic keys the number of growth keys increasing as the diameter of a row approaches the diameter of the growth ring and beyond the diameter

of the growth ring, each row having added thereto straights with combinations of said keys, the number of keys in each row of a course being constant, the limiting rows of successive courses comprising brick of different length, and the brick in successive courses being laterally offset with respect to those adjacent courses, whereby vertical joints are broken.

5. A brick furnace lining of non-uniform diameter circular in horizontal section comprising horizontal courses each consisting of a plurality of concentric rows of brick, said brick comprising straights and keys, the straights including two related lengths of equal width, the keys comprising a basic set and a growth set, said basic set being sectors in two lengths of equal inner width of a basic ring the diameter of which is that of a basic 10 minimum furnace opening, said growth set comprising sectors in two lengths of equal inner width of a growth ring concentric with and of greater diameter than said basic ring, the lengths of said keys being the same as 15 the lengths of the straights, said basic and growth keys being equiangular, the inner row of a course of basic diameter containing only basic keys, the number of keys in each row of a course being constant, the inner diameter of each row successive to an inner row 20 up to that of the growth ring being substantially equal to the outer diameter of the next row inwardly and having growth keys combined with basic keys, the number of growth 25 keys increasing as the diameter approaches that of the growth ring, and those beyond the growth ring containing straights with combinations of said keys, and the limiting rows of successive courses being of different length 30 brick.

6. A furnace lining according to claim 5, the rows of a course intervening between its limiting rows being chosen so as to break joints vertically with the bricks in adjacent courses, and all the bricks in a row being of the same length.

7. A brick furnace lining of non-uniform diameter circular in section comprising successive courses each comprising a plurality 35 of concentric rows of brick, said brick comprising key bricks and straights, said straights comprising two lengths of equal width, said key bricks comprising basic keys and growth keys, said basic keys being sectors in two lengths and of equal inner width 40 of a ring of basic minimum diameter, said growth keys comprising sectors in two lengths and of equal inner width of a ring concentric with and of greater diameter than said basic 45 ring, all of said lengths being integral multiples of a common divisor, and all of said keys having the same central angle, said bricks being adapted for the construction of linings of any diameter equal to or greater than that 50 of the basic ring, and of any thickness being

a multiple of the length factor, in such manner that the inner diameter of each row of a course outwardly is the same as the outer diameter of the next row inwardly, each row in a course containing the same number of keys, and the bricks in successive courses being staggered and overlapped, whereby all joints are broken.

8. A furnace lining which is tapered and which is circular in horizontal cross section made up of horizontal courses of brick arranged in concentric rows, the brick comprising a set of basic keys in two lengths, the keys being sectors of a circle of basic diameter, a set of growth keys in two lengths corresponding to the basic keys and being sectors of a circle of greater diameter than the basic circle, the basic keys and the growth keys being equiangular, a set of straight brick of two lengths corresponding to the lengths of the keys, each row in a course whose diameter is greater than the diameter of the basic circle and less than the diameter of the growth circle being comprised of basic and growth key bricks, and beyond the diameter of the growth circle comprised of basic and growth keys and straight brick, the rows of every course containing the same number of key bricks.

9. A furnace lining which is tapered and which is circular in horizontal cross section made up of horizontal courses of brick arranged in concentric rows, the brick comprising a set of basic keys in two lengths, the keys being sectors of a circle of basic diameter, a set of growth keys in two lengths corresponding to the basic keys and being sectors of a circle of greater diameter than the basic circle, the basic keys and the growth keys being equiangular, a set of straight brick of two lengths corresponding to the lengths of the keys, each row in a course whose diameter is greater than the diameter of the basic circle and less than the diameter of the growth circle being comprised of basic and growth key bricks, and beyond the diameter of the growth circle comprised of basic and growth keys and straight brick, the rows of every course containing the same number of key bricks.

10. A tapering brick furnace lining circular in horizontal section comprising horizontal courses each consisting of a plurality of concentric rows of brick, said brick comprising straights and keys, the straights including two related lengths of equal widths,

the keys comprising a basic set and a growth set, said basic set being sectors in two lengths of equal inner width of a basic ring, the diameter of which is that of a minimum 5 basic furnace opening, said growth set comprising sectors in two lengths and of equal inner width of a growth ring concentric with and of greater diameter than the said basic ring, the lengths of said keys being the same 10 as the lengths of the straights, the basic and growth keys being equiangular, the inner row of a course of basic diameter containing only basic keys, other rows of greater diameter being developed first by substituting 15 growth keys for basic keys, and beyond the diameter of the growth ring by adding straights with combinations of said keys, the number of keys in each row of a course being constant, the rows of successive courses comprising brick of different lengths, and the brick in successive courses being laterally offset with respect to those in adjacent courses 20 whereby vertical joints are broken.

In testimony whereof, I sign my name.
25 JAMES C. MOREHEAD.
